Attorney

UNITED STATES PATENT OFFICE.

THOMAS SLEVIN, OF ST. LOUIS, MISSOURI.

VEHICLE.

SPECIFICATION forming part of Letters Patent No. 424,365, dated March 25, 1890.

Application filed February 13, 1888. Renewed March 26, 1889. Again renewed November 7, 1889. Serial No. 329,487. (No model.)

To all whom it may concern:

Be it known that I, THOMAS SLEVIN, a citizen of the United States, and a resident of St. Louis, in the State of Missouri, have invented 5 certain new and useful Improvements in Devices for Transportation; and I do declare the following to be a full, clear, and exact description of the invention, such as will enable others skilled in the art to which it appertains to 10 make and use the same, reference being had to the accompanying drawings, and to letters of reference marked thereon, which form a part of this specification.

Figure 1 of the drawings is a representation 15 of a plan view of my improved transport. Fig. 2 is a side elevation of same. Fig. 3 is a vertical section on line $x x$, Fig. 1.

The invention relates to devices for transporting heavy loads; and it consists in the 20 construction and novel combination of parts, as hereinafter specified.

The object of my invention is to provide a 25 means for conveying heavy loads—such as iron safes, large stones, buildings, &c.—whereby the weight of the load will be distributed over a larger area of ground-surface than is possible with ordinary wheels.

Referring to the drawings, A designates a 30 roller-way, which may be of any desired length, rigidly bolted or secured, as at a, to the side pieces B. The said side pieces extend above and below the roller-way, and also project in front and in the rear thereof, where they are joined by the end pieces C. 35 The end pieces C near their extreme ends are provided with the openings a', designed to embrace the side pieces, as shown, and brace-bars b connect the end pieces. The parts B and C, when put together, form a rectangular frame, within which the roller-way is located. The roller-way A has its upper and lower sides parallel and its front and rear sides rounded in cross-section.

D represents a series of parallel rollers provided 40 at their ends with journals b', bearing in loose sleeves c. The heads c' on the ex-

treme ends of the journals bear slightly against the inner surfaces of the side pieces B, and thus keep the rollers in a direct course around the roller-way. Flexible end- 50 less bands E pass completely around the roller-way, the sleeves c being secured to the bands E at equidistant points. By this construction an endless chain of rollers is provided to revolve around and bear upon the 55 roller-way, and the pressure on the ground is distributed to all the rollers coming between the way and the ground.

The device above described may be drawn in either direction by horse-power or otherwise, 60 and eyebolts d are attached to each end of the pieces B, as shown, to which draft-chains may be connected.

Having described my invention, what I claim is—

1. In a transporting device, the combination 65 of the rectangular frame, the roller-way secured therein having the parallel sides and the rounded sides, and the connected parallel rollers having the journals b' and the heads, 70 substantially as specified.

2. In combination with the rectangular frame, the roller-way secured therein, the parallel rollers having the journal portion and the head, the sleeves engaging loosely 75 the said journals, and the flexible bands, substantially as specified.

3. The combination of the frame consisting 80 of the side pieces B and the end pieces C, the roller-way rigidly bolted to the side pieces, the brace-bars b, the series of parallel rollers having the journal portions and the head, the flexible endless bands, and the sleeves secured to said bands at equidistant points and loosely engaging the journals of 85 the rollers, substantially as specified.

In testimony whereof I affix my signature in presence of two witnesses.

THOMAS SLEVIN.

Witnesses:
